AUGUST J. KLONECK, OF NEW YORK, N. Y.

ROTARY SPARK-GAP.

1,382,786.

Specification of Letters Patent. Patented June 28, 1921.

Application filed June 3, 1916. Serial No. 101,560.

To all whom it may concern:

Be it known that I, AUGUST J. KLONECK, a citizen of the German Empire, and a resident of New York, in the county of New 5 York and State of New York, have invented certain new and useful Improvements in Rotary Spark-Gaps, of which the following is a specification.

This invention relates to mechanical apparatus for varying electrical currents and more particularly to that, whereby a high tension electrical current will be modified in frequency and character by mechanical means.

15 One object of this invention is to provide an apparatus, whereby a high tension electrical current will simultaneously be interrupted at a plurality of points.

Another object of the invention is to provide 20 an arrangement of electrodes to produce a current of high frequency with a low number of electrodes.

These and other allied objects are attained 25 by the novel arrangement and combination of parts hereinafter described and clearly indicated in the accompanying drawings in which:

Figure 1 is a top view of a preferred form 30 of apparatus, showing certain novel mechanical elements, parts of said apparatus being shown in section.

Fig. 2 is a diagrammatic view, showing the arrangement of breaking points to produce a low frequency electrical current.

35 Fig. 3 shows a diagrammatic view of an arrangement of breaking points to produce a high frequency electrical current.

Fig. 4 shows an arrangement of breaking points to produce an electrical current of 40 medium frequency.

Fig. 5 shows a diagrammatic view of breaking points to produce current of a lower frequency alternately reversing with respect to two of four terminals.

45 Like parts are indicated by similar characters of reference throughout the specification and in the drawings—

Referring more particularly to Fig. 1, the numerals 1 and 2 represent two disks of 50 suitable material, each having one of its surfaces opposed to one of the other. Electrode sets 3 and 4 are attached one to each of said disks and in operative relation with one another. Other independent electrode sets 55 5 and 6 will be arranged on said disks,

and insulated from the spark set 3, 4. Both spark sets will be used simultaneously in a combination as convenient or desired. The electrodes 3 and 4, for instance, serve for the completion and interruption of one electrical circuit, supposedly comprising the terminals or posts 7 and 8 of said set. The latter correspond with terminals 7 and 8 of Figs. 2, 3 and 4. The electrode set 5, 6, however, is shown with four 60 posts 9, 10, 11 and 12, the purpose of which will be explained in connection with Fig. 5. Either one or both disks 1 and 2 will be rotated, if desired. The frequency of current interruptions will be doubled, if both 65 disks are oppositely rotated with respect to one another. For this purpose, the electrode carrying disks may be rotated by one or more suitable driving means 13, as electric motors, or fluid turbines, or driven by a 70 pulley, gears or clutches 14; further, the shafts 15 and 16, and belts 17 and 18 may serve to rotate said disks. In the present application the electrical current is supposed to bridge small gaps between stationary electrodes 19, 20 and the collecting ring electrodes 21 and 22, for instance.

The latter collect current for the terminals 7 and 8 for one electrode set. The other spark sets may be either such of Fig. 2, Fig. 85 3 or Fig. 4.

In Figs. 2, 3, 4 and 5 it will be noted that the electrodes are shown as one ring set within the other, however, I prefer to arrange the same parallel to each other as indicated 90 in Fig. 1.

In Fig. 2, the numerals 3 and 4 represent the two ring sets of electrodes, forming an operating means for the interruption of an electrical current. Each ring is subdivided 95 into sections 3^a, 3^b, 4^a, 4^b. The ring set 3, for instance, comprises four sections 3^a, 3^b, 3^c, and 3^d, of which the terminal sections 3^a and 3^d, for instance, are connected to the terminals 7 and 8, and comprise two spark 100 points each one while each of the intermediate sections, 3^b and 3^c, has four spark points. The ring set 4 in this figure comprises three sections, 4^a, 4^b, and 4^c, each of two spark points. The purpose of this subdivision is 105 to interrupt an electrical current at a plurality of points in series with one another simultaneously while retaining the high number of current interruptions receivable with the aforesaid subdivision of electrodes. 110

In this figure it will be seen that an electrical circuit is established from terminal 7 and electrode 3^a to 4^a, then 3^b, further through 4^b to the other terminal 8 by electrode 3^d. Thus, an electrical current will be interrupted at four points simultaneously.

In Fig. 3, the ring set 3 comprises 30 spark points and is divided into 6 sections of which the terminal sections have each three points, 10 and the intermediate sections 3^b and 3^c have each six spark points while the ring set 4 has 20 spark points arranged in 5 electrode sections of each four points, whereby an electrical current will be interrupted at six 15 points in series of each other, simultaneously, between 3^a and 4^a, 4^a and 3^b, 3^b and 4^b, 4^b and 3^c, 3^c and 4^c, and 4^c and 3^d, respectively. In this figure I have employed an arrangement and number of electrode or spark points 20 whereby the produced number of spark gap interruptions is greater than the number of spark breaking points employed. While the greatest number of points is thirty on disk 3, the number of interruptions will be sixty 25 for one revolution of each ring set 3 or 4, or 120 for one revolution of both rings, respectively. Such system has been described in my Patent, No. 1,263,073, of April 16, 1918, and consists in employing a certain 30 number of breaking points whereby the number of interruptions is equal to the least common multiple of the number of points on each disk.

In the present construction the discharging current is broken at a plurality of intermediate points in series and at the terminals simultaneously.

Fig. 4 illustrates an arrangement of 18 points in four sections of ring 3, while ring 40 4 has 12 points in three sections. The number of interruptions will be 36 for one revolution of each ring set. Another novel feature, consisting of producing a sound made up of two or more separate tones of a signal will in connection with this figure be explained. Suppose certain points, as for instance, every second point of the section set 4 are displacedly arranged so that there will be two distances 23 and 24 between two 45 successive spark points. Thence, these two distances cause discharges of current at two different time intervals of two successive sparks, the difference of time intervals corresponding to the difference of distances 23 and 24 of the spark points. The result 50 will be a double tone or a double pitch of the sound of a signal produced by interruptions of an electrical current. Suppose now, every third point of a certain number 55 of spark points is displacedly arranged, as for instance, every third electrode point of the section set 3 is displaced. Thence there will be three distances of spark points and time differences 25, 26, and 27 of three successive 60 current discharges, which if ring 3

had only the spark points arranged in three distances or a multiple of three distances would produce a triple tone or pitch of the sound in telephone receivers as a result of the reproduced interruptions of electrical current. Suppose now, said electrode points of both sections 3 and 4 are displaced. The result will be a compound note made up of several notes whose frequencies are determined by the distances 23, 24—25, 26 and 27 of spark points. As the spark points may be arranged to have any desired distances with respect to one another the current discharges may be made to produce a sound of any desired character or any musical note.

It will be obvious that any difference of time intervals or distances and tones may thus be obtained, such possibilities being too various to illustrate or describe.

In Fig. 5, the numerals 5 and 6 represent two section sets for a spark gap whereby current from a source connected across the terminals 9 and 10 will be interrupted and reversed in direction for the terminals 11 and 12, alternately. Thus, said two wire circuit from 9 and 10 for terminals 11 and 12 will be interrupted at 8 points simultaneously, and in series with the two pole conductors which in the shown position include the spark gaps a, b, c, d, e, f, g, and h. An alternate position of electrode set 6 whereby the direction of an electrical current will be reversed is produced by $\frac{1}{2}$ revolution of electrode set 6. Thus, current 100 from terminal 9 then will flow by gaps a, i, k and h to terminal 12, and current from terminal 10 will flow by gaps e, m, l, and d to terminal 11 of said gap.

It will be noted that the spark gap shown 105 in Fig. 1 comprises two complete spark gap sets, one between 3 and 4 and the other between 5 and 6. Further, Fig. 5 shows spark gaps 9—11, 9—12, 10—11 and 10 to 12 which may be used separately if desired. One use 110 of such spark gap is described in my application Serial No. 96,228, filed May 8, 1916, where two spark gaps are employed; one for connecting a transformer with a source of current and the other for short circuiting 115 said transformer alternately. By employing the spark gap of Fig. 5 for this purpose, thence two separate spark gaps are attained between terminals 10—12 and 9—12 for instance.

Having fully described my invention that what I claim as new and desire to secure by Letters Patent is:

1. A rotary spark gap, comprising two motors having their shafts in axial alignment with one another, electrode holders attached on each shaft carrying metallic electrodes thereon, the electrodes of one motor co-operating with the electrodes of the other motor, said electrodes being divided 125

into sections having a plurality of projecting points, the total number of electrode points being different for each holder.

2. In a rotary spark gap, two oppositely arranged electrode holders of insulating material having a plurality of electrodes thereon, one of said holders having four terminal electrodes in operative relation with one another, the same being arranged one at each 10 quadrant, and conducting electrodes located between each two terminal electrodes, the electrodes on the other holder being arranged to connect one terminal electrode with one terminal electrode of one of the two adjacent quadrants by means of said conducting electrodes.

3. A rotary spark gap, comprising two opposing electrode holders of insulating material having metallic electrodes arranged 20 thereon in sections insulated from each other, each section having a plurality of projecting spark points, the total number of spark points being different for each holder, one holder carrying terminal sections, the other 25 holder having connecting electrode sections therefor.

4. In combination with a spark gap, a system of producing a musical note in receivers by reproduced periodically similar 30 spark discharges of a spark gap, the latter having certain successive spark points spaced in different distances with respect to adjacent spark points of the same set and other spark points for connecting said differently 35 spaced spark points successively, causing different time intervals to elapse between successive current discharges between said spark points.

5. In a rotary spark gap, a plurality of 40 projecting spark points arranged upon two holders adapted for successive operative connection with one another, the distances between certain successive connecting spark 45 points varying from one another for producing certain varying time intervals of successive sparks.

6. In a rotary spark gap, a plurality of projecting spark points arranged upon two holders adapted for successive operative connection 50 with one another, one holder comprising terminal spark points and the other connecting spark points therefor, certain successive connecting spark points being spaced differently from one another for producing 55 varying tones of sound in a receiving instrument by similar time intervals of successive current discharges between said spark points and a note of sound in receivers comprising different tones.

60 7. In a rotary spark gap, a plurality of projecting spark points arranged upon one holder of insulating material adapted for successive operative connection with spark points of another holder, certain successive 65 connecting spark points upon said holders

being spaced at different distances from one another adapted for producing a compound note of sound in receiving instruments by similar time intervals of successive current discharges of said successively connecting 70 spark points, certain of said spark points being arranged to form a plurality of insulated sections upon each holder, successive sections of spark points upon one holder connecting spark points of sections arranged 75 oppositely thereto upon the other holder.

8. In a rotary spark gap, a plurality of projecting spark points arranged upon two holders adapted for successive operation of certain spark points at successive different 80 time intervals, which spark points are spaced at different distances with respect to one another, adapted for producing current discharges therebetween having different time intervals from one another, said spark points 85 being arranged in sections upon opposing holders, one holder having terminal sections and intermediate sections, another holder having connecting sections of spark points for said terminal sections of spark points of 90 said first mentioned holder.

9. In a rotary spark gap, a plurality of projecting spark points arranged upon one holder adapted for successive operation by spark points arranged upon another holder, 95 the spark points upon said first mentioned holder being placed at different distances with respect to adjacent spark points adapted for producing discharges of current between the spark points of said two holders 100 having a differing time interval successively for producing a compound note of sound of a signal in receiving instruments, said spark points being arranged upon opposing holders, each holder having spark points differently spaced from the spark points on the other holder.

10. In a rotary spark gap, a plurality of projecting spark points, arranged upon separate holders of insulating material, certain spark points upon one holder being arranged for successive operative connection with spark points of an opposing holder, adjacent spark points having the distances from one another varying for producing successively different time intervals between the operative connection of such spark points, said spark points being arranged in sections upon opposing holders, one holder comprising terminal sections and intermediate sections, the opposing holder having connecting spark point sections therefor adapted for connecting said terminal and said intermediate sections in series with one another, each of said intermediate sections comprising a 110 number of spark points twice that of each of said terminal sections.

11. In a rotary spark gap, a plurality of spark points forming two independent spark gaps, the latter being insulated from one 130

- another, having certain spark points arranged in sections insulated from one another.
12. In a rotary spark gap, a plurality of 5 spark points forming two independent spark gaps, the latter being insulated from one another and in operative relation with one another, having certain spark points arranged upon opposing holders in sections the 10 sections of said opposing holders coöperating in series with one another.
13. In a rotary spark gap, a plurality of 15 insulated holders, a plurality of metallic spark points arranged upon each of said holders in separate sections, certain sections of spark points of one holder coöperating with sections of spark points of another holder, said coöperating sections and spark points of one holder comprising terminals 20 arranged at each quadrant, the other holder having connecting spark point sections therefor arranged in a manner for connecting one of the opposite terminals with one of the adjacent terminals.
14. A rotary spark gap, comprising two 25 motors having insulated metallic electrodes arranged upon their shafts, the electrodes of said motors being in operative relation with one another and arranged in insulated 30 sections, said sections having a plurality of projecting spark points thereon, said spark points being differently spaced upon the holder of each motor.
15. A rotary spark gap comprising two 35 motors having insulated metallic electrodes arranged upon their shafts, the electrodes of said motors being in operative relation with one another and arranged in insulated 40 sections, said sections having each a plurality of projecting spark points thereon, certain adjacent spark points upon certain of said sections being differently spaced from one another.
16. A rotary spark gap comprising two 45 motors having insulated metallic electrodes arranged upon their shaft, the electrodes of said motors being in operative relation with one another, said electrodes having a plurality of projecting spark points, certain numbers 50 of successive spark points being arranged at different distances from one another adapted for producing current discharges successively at different time intervals.
17. In a rotary spark gap, two electrode 55 holders having a plurality of insulated electrodes arranged thereon in sections, sections of electrodes of said two holders coöperat-
- ing in series with one another, each of said sections having a plurality of spark points, one holder having terminal sections and intermediate sections, each of said intermediate sections comprising twice the number of spark points of each of said terminal sections. 60
18. In a rotary spark gap, two electrode 65 holders having a plurality of electrodes and spark points arranged in sections, one holder having terminal sections at opposite points, and sections arranged intermediate said terminal sections, the number of spark points 70 on each of said intermediate sections being twice the number of spark points on each of said terminal sections, the other holder having sections for connecting said intermediate sections in series with said terminal 75 sections, the distances of spark points from one another being different for each holder. 80
19. The combination with a rotary spark gap, one electrode holder having a plurality of terminal electrodes, another holder having connecting electrodes therefor having a plurality of projecting spark points, and stationary electrodes, each of said terminal electrodes comprising projecting spark point electrodes and collecting ring electrodes, the latter forming a spark gap with 85 said stationary electrodes. 90
20. The combination with a rotary spark gap, one electrode holder having terminal electrodes, another holder having connecting electrodes having a plurality of spark points, said terminal electrodes having a plurality of spark points, the spark points being differently spaced from one another upon 95 each holder. 100
21. The combination with a rotary spark gap, of stationary spark points, said rotary spark gap including electrode holders of insulating material having metallic electrodes arranged thereon, certain of said electrodes have a plurality of projecting spark points, certain others being plain collecting ring electrodes, the latter being adapted to form a conducting current spark gap with 105 said stationary spark points for the projecting spark point electrodes. 110

In testimony whereof I hereunto subscribe my name to this specification in the presence of two witnesses.

AUGUST J. KLONECK.
